his Attorney.

UNITED STATES PATENT OFFICE.

FRANK M. GILBERT, OF OREGON, ILLINOIS.

FUMIGATOR.

1,151,353.

Specification of Letters Patent. Patented Aug. 24, 1915.

Application filed December 12, 1913. Serial No. 806,171.

To all whom it may concern:

Be it known that I, FRANK M. GILBERT, a citizen of the United States, and a resident of the city of Oregon, county of Ogle and State of Illinois, have invented certain new and useful Improvements in Fumigators, of which the following is a specification.

My invention relates to fumigating devices, and more specifically to that class thereof designed for use especially in greenhouses for exterminating insects, lice and other destructive bugs found upon the leaves of plants and which if permitted to flourish injure or destroy the plant.

The object of my invention is the production of a fumigator, as mentioned, which will be durable and economical in construction, and through the medium of which the fumigation of a greenhouse may be thoroughly and affectively effected.

Other objects will appear hereinafter.

The invention consists in the combinations and arrangements of parts hereinafter described and claimed.

The invention will be best understood by reference to the accompanying drawing forming a part of this specification, and in which,

Figure 1 is a side elevation of a fumigator embodying my invention, Fig. 2 is a central vertical section thereof, and Fig. 3 is a horizontal section of the fumigator.

The preferred form of construction as illustrated in the drawing comprises a receptacle consisting of a circular or cylindrical lateral wall 1 formed of a heavy wire mesh or hardware cloth. The upper end of the receptacle is closed by a circular imperforate plate 2 and at the lower end of said lateral wall is provided a reinforcing ring or band 3. A plurality of longitudinally extending straps 4 are provided which extend along the lateral wall 1 exteriorly thereof for reinforcement, said straps being secured to the top wall member 2 and the ring 3 by means of rivets 5. Said rivets 5 also serve to secure the lateral wall 1 to the member 2 and ring 3, the resulting construction possessing great firmness and rigidity. Upon the upper side of the top wall 2 is provided a turn down handle 6 whereby the fumigator may be readily transported or moved from place to place.

The lower end of the receptacle is open, the bottom 7 thereof being hingedly secured at 7' to one of the reinforcing straps

4 in order to permit of access being gained to the interior of said receptacle, as will be readily understood. A spring latch or keeper 8 cooperates with the bottom 7 to releasably lock the same in closed position. Said bottom is provided with an upwardly extending peripheral flange so as to adapt said bottom to serve in the capacity of an ash receptacle during operation of the fumigator, the ashes of the consumed tobacco stems which are used in the receptacle in operation being adapted for reception in said bottom to thus prevent spreading upon the floor or other surface upon which the device is arranged.

Arranged centrally upon the upper side of the bottom 7 is an elongated torch 9 consisting of an elongated hollow body secured in position by straps 10, a wick of asbestos or other suitable material being provided within said body. The upper side of said torch body is perforated so as to permit of jets issuing therefrom in the operation of the fumigator. The bottom 7 is perforated as shown, so as to permit of the draining of water therefrom during the operation of the fumigator in the manner described in the following. In the operation of the fumigator, the receptacle is first packed full of tobacco stems, such packing being of course permitted through the lower end of the receptacle by reason of the hinged mounting of the bottom 7. After the arrangement of the tobacco stems in the receptacle, the latter is inverted, and the lower end thereof immersed in water. The handle 6 is of the turn down type in order to permit of the receptacle being stood on its upper end, when inverted, as will be readily understood. In this immersion of the receptacle about three-fourths of the contents thereof will be saturated with water. After the tobacco stems have been thoroughly saturated, the receptacle is removed from the water and again placed upright, the tobacco stems in the lower end thereof being dry, not having been immersed. In this immersion of the upper end of the device, about two quarts of water will be absorbed by the tobacco stems. After removal from the water, the saturated stems are permitted to drain, the water draining therefrom passing downwardly into the dry stems below effecting simply a dampening of the latter. Some of the water will pass completely through the contents of the receptacle and into the bot-

tom 7, being permitted to drain from the latter through the openings which are provided therein for this purpose. The torch 9 is now lighted which of course ignites the dry or slightly moistened tobacco stems in the lower end of the device. The heat of the combustion below effects vaporization of the water contained in the saturated stems above and this vapor, which is laden with nicotin 10 together with a dense smoke which will be emitted from the burning tobacco stems at the base of the device, permeating the atmosphere of the room and effecting the destruction of any insects with which the 15 same may be brought into contact. The combination of the nicotin vapor which is emitted from the dampened tobacco stems above, and the dense smoke which is emitted from the dry tobacco stems below, produces a very effective insect destroyer and without injuring the plants themselves. As 20 above mentioned, in the saturation of the tobacco stems in the upper end of the receptacle about two quarts of water is absorbed and which, when heated through the combustion below, results in the formation of a considerable quantity of nicotin laden vapor, as will be readily understood.

After the torch has been lighted, as above 30 mentioned, the fumigator is entirely automatic in its operation, the tobacco stems being gradually consumed in the manner illustrated in Fig. 2 of the drawing.

While I have illustrated and described 35 the preferred form of construction for

carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention what I claim as new and desire to secure by Let- 45 ters Patent is:

1. A fumigator comprising a receptacle having openings in the walls thereof; a closure movably mounted at one end of said receptacle through which access may be gained to the interior thereof; and an igniting element secured to the upper side of said closure, substantially as described.

2. A fumigator comprising a receptacle having openings in the lateral walls thereof and being open at its lower end; a closure hingedly mounted at said end of said receptacle through which access may be gained to the interior of said receptacle; means for releasably locking said closure in closed position; and an elongated torch secured centrally upon the upper side of said closure, substantially as described.

In testimony whereof I have signed my name to this specification in the presence of 65 two subscribing witnesses.

FRANK M. GILBERT.
